UNITED STATES PATENT OFFICE.

LEONARD L. PARRY, OF MANSFIELD, OHIO.

ARTIFICIAL-STONE OR CONCRETE RECEPTACLE FOR CASKETS.

SPECIFICATION forming part of Letters Patent No. 738,696, dated September 8, 1903.

Application filed November 6, 1902. Serial No. 130,288. (No model.)

To all whom it may concern:

Be it known that I, LEONARD L. PARRY, a citizen of the United States of America, and a resident of Mansfield, county of Richland, and State of Ohio, have invented certain new and useful Improvements in Artificial Stone or Concrete Receptacles for Caskets, of which the following is a specification.

My invention relates to receptacles which are used for inclosing caskets or coffins; and the objects of my invention are, first, to provide a means of constructing an air and water tight receptacle; second, to construct a receptacle of artificial stone or concrete in conjunction with wire-cloth by means of which additional strength and durability is obtained without increasing the weight or the use of additional material; third, to afford facilities for placing the lid of the receptacle in place preparatory to sealing. I attain these and other objects by the construction of the receptacle as shown, and illustrated in the accompanying drawings, in which—

Figure 1 is a perspective view of my invention, portions being broken away to show the wire-cloth and the manner of securing the bars in the material of which the top is constructed. Fig. 2 is a cross-sectional view taken on the line $\alpha\alpha$ of Fig. 1.

1 indicates a receptacle constructed in accordance with my invention and of any suitable form, but preferably rectangular. The receptacle comprises an integral box 2, which is both air and water tight, and a lid 3, fitting closely thereupon. The material of which the receptacle is composed may be concrete or other plastic material which when dry is hard and strong. In manufacturing these receptacles a wire-cloth bond 4 is formed into the desired shape and placed in a mold. The concrete or other plastic material is then placed into the mold, the particles of plastic material uniting with each other through the interstices or meshes of the wire-cloth and around the strands in such a manner that the wire-cloth is embedded between the inner and outer surfaces of the receptacle and forms an additional strengthening means therefor. The upper edge of the box 2 is provided with a groove or recess comprising an internal shoulder 5 and an oblique or inwardly-inclined wall 7.

The lid or cover 3, which may be flat or arched, is made in the same manner as is the box, with the exception that the wire bond is provided near each end with apertures. Embedded in the material of which the cover is made and beneath the wire bond are rods 8, which may be located in alinement with the apertures formed in the wire bond and near the edges of the lid or cover and extending parallel therewith, as shown. Likewise firmly embedded in the lid or cover are loop-bars 9, which may extend transversely of the lid, as shown, these bars being located beneath the wire bond and provided with or formed with loops 10, which pass through the apertures formed in the wire bond and extend above the surface of the lid or cover. The ends 11 of the loop-bars are bent into hook shape and engage the embedded rods 8. The arch shape of the lid or cover is preferred because of its maximum strength. The edges of the cover are provided with bearing-surfaces 12 of the same width as the shoulder 5, which bearing-surfaces are received and rest upon the shoulder 5, the periphery 14 of the cover being approximately perpendicular, so that when the cover is placed upon the box a wedge-shaped recess 13 is formed between the inclined wall 7 and the perpendicular periphery 14 of the cover, which recess is designed to receive some sealing material, as cement, mortar, &c.

From the above description it will be observed that the loops 10 are for the reception of means whereby the lid may be lifted on or off the box, the body portion of the bars conforming to the shape of the lid, and the retention of the hooked ends 11 of the bars beneath the rods 8 serving to equalize the strain in moving the lid.

It will be evident that changes might be made in the form and arrangement of the several parts described without departing from the spirit and scope of my invention, and hence I do not wish to limit myself to the exact construction herein set forth; but,

Having thus fully described my invention, what I claim as new, and desire to secure by Letters Patent, is—

1. A receptacle comprising a box and a lid or cover therefor, each composed of plastic material, apertured strengthening means em-

bedded within the plastic material, a bar having a handle formed thereon embedded within the cover, the body portion of the bar located beneath the embedded strengthening means, 5 the handle extending through the aperture in the strengthening means and projecting above the surface of the cover.

2. A receptacle comprising a box and a lid or cover, each composed of plastic material, 10 apertured strengthening means embedded therein, a bar having a handle formed thereon, the bar embedded in the cover and conforming in shape to the cross-sectional contour of the cover, the body portion of the bar located 15 beneath the strengthening means, the handle received in the aperture in the strengthening means and projecting above the surface of the cover.

3. A receptacle comprising a box and a lid 20 or cover, each composed of plastic material, apertured strengthening means embedded therein, looped bars embedded in the cover and having hooks formed in the ends thereof, the body portions of the bars located beneath

the strengthening means, means embedded 25 in the cover, the hooks on the bars adapted to engage the embedded means, the looped portions of the bars received in and extending through the apertures in the strengthening means and projecting above the surface of 30 the cover.

4. In a receptacle, the combination with a box and a lid or cover, of a hooked bar having a handle formed thereon, the bar embedded in the material of which the lid is constructed, 35 and auxiliary means likewise embedded in the material of which the lid is formed, the hooked bar engaging the auxiliary means, the handle on the bar projecting outside the surface of the material of which the coffin is 40 formed.

Signed at Mansfield this 1st day of November, 1902.

LEONARD L. PARRY.
